UNITED STATES PATENT OFFICE.

RICHARD M. BEDELL, OF BROOKLYN, NEW YORK, ASSIGNOR TO MERTENTHALER LINOTYPE COMPANY, A CORPORATION OF NEW YORK.

LINOTYPE-MACHINE.

No. 811,362.

Specification of Letters Patent.

Patented Jan. 30, 1906.

Application filed October 18, 1905. Serial No. 283,255.

To all whom it may concern:

Be it known that I, RICHARD M. BEDELL, of Brooklyn, county of Kings, and State of New York, have invented a new and useful Improvement in Linotype-Machines, of which the following is a specification.

This invention has reference to linotype-machines of the general organization represented in Letters Patent of the United States No. 640,033, wherein there are two magazines for the matrices, one overlying the other and each combined with a distributing mechanism, through which the matrices are delivered thereto. In these machines as commercially built the composed lines of matrices are presented to a separating mechanism such as shown in Letters Patent of the United States No. 767,169, whereby matrices of the upper magazine are delivered directly to the upper distributor-bar, while the matrices for the lower magazine are permitted to drop clear of said bar to pass downward of the distributing mechanism of the lower magazine. In this mechanism the matrices of the lower magazine are provided in the lower end with a notch, while the matrices of the upper magazine are made without this notch. As the machines and matrices have been heretofore constructed it was impossible to run the matrices intended for one magazine in the other. In practical operation of the machine it is sometimes desirable that this change shall be made and that the matrices intended originally for one of the magazines shall be used for the time being in the other.

The present invention relates to means whereby the path of the font or set of matrices may be changed so that it will pass into the upper or the lower magazine, as demanded.

I have represented herein two embodiments of my invention which are found in practice to answer their purpose; but it will be understood by the skilled mechanic that the constructions may be widely varied without changing the operative principle.

The drawings herein are limited to those parts of the machine with which my improvement is directly associated, and it will be understood that the other parts may be of any suitable construction.

Referring to the drawings, Figure 1 is a perspective view of the receiving end of the upper distributor-bar and the attendant de-

vices adjusted to deliver the matrices to the said bar. Fig. 2 is a cross-section of the same on the line 2 2 of Fig. 1, but with the matrix-support reversed, so that the matrices will escape or fail to engage the distributor-bar. Fig. 3 is a view similar to Fig. 1, showing, however, matrices with two notches instead of one in the base and with the support correspondingly constructed, the support being in position to permit the matrices to pass clear of the distributor-bar. Fig. 4 is a cross-section on the line 4 4 of Fig. 3, but with the matrix-support reversed, so that the matrices are caused to engage the bar.

In Figs. 1 and 2, X represents the ordinary Mergenthaler distributor-bar fixed in position and having its lower edge of V form provided with longitudinal teeth. Y represents the matrices constructed, as usual, with a V-shaped notch in the upper end and teeth therein to engage the teeth of the distributor-bar. The teeth of the bar are permuted in arrangement, and the teeth of the matrices bearing the different characters are varied in number and arrangement accordingly, so that each matrix carried along the bar may be suspended by its teeth until it arrives at the proper point for delivery to the magazine below. x x are fixed side rails commonly employed in the distributor-box for supporting the composed line of matrices as they are moved horizontally toward the distributing mechanism. Each of these rails is made, as usual, with a vertical shoulder x', against which the foremost matrix in the line is presented until it is lifted by the usual device. As each matrix is lifted clear of the shoulders x', it is moved forward along the elevated ends of the rails x at a proper height for its teeth to engage those of the bar X. The forward ends of the bars X are, however, recessed or cut down on top, as shown at x², so that each matrix in passing forward is permitted to fall, so that its teeth will escape those of the bar X unless an additional support is provided below the under end of the matrix.

All of the foregoing parts are constructed and arranged to operate in the same manner as the parts indicated by like letters in Patent No. 767,169. The matrices intended to escape the upper distributor X and pass ordinarily to the lower distributor are constructed,

as heretofore, with a notch y in the lower end. Heretofore a stationary bridge or support has been used below the path of the matrices in such form that it could be straddled by 5 the notched matrices Y , while, on the other hand, it served to maintain the unnotched matrices and carry them to the upper distributor X . I now substitute for this stationary bridge or support Z of said patent a reversible or adjustable bridge or support A , mounted on a horizontal pivot and provided with a milled head a , by which it may be rotated and reversed. On one side this bridge is provided with a central rib a' of suitable 10 size to enter the notches in the lower ends of the matrices, as shown in Fig. 2, while on the opposite side it is provided with one or more raised surfaces a'' , adapted to underlie the advancing matrices outside of their notches. 15

20. When the bridge is set in the position shown in Fig. 1, with the ribs a'' uppermost, the advancing matrices will ride upon these ribs and be sustained thereby at a high level, so that their teeth will engage those of the 25 bar X in order that the matrices may be delivered to the upper magazine. When, however, the bridge is reversed, so that the rib a' is uppermost, as shown in Fig. 2, the advancing matrices will be permitted to fall 30 astride of the rib, so that the teeth at their upper ends will fail to engage those of the bar X . This will permit the matrices to move forward until they have passed the bridge, when they are free to descend to the lower 35 distributor, as heretofore.

The essence of the invention lies in the employment of an adjustable or reversible bridge or support A , which will in one position sustain the matrices at a high level and in another position permit them to advance at a low level.

To prevent accidental movement of the bridge A , I propose to employ any suitable locking mechanism—such, for example, as the 45 spring a^4 , fixed to a stationary part of the machine, and having at one end a tooth to enter the notches a^5 in the spindle of the bridge.

In Figs. 3 and 4 I have shown a mechanism similar to that in the preceding figures, the only difference being that the matrix is provided with three notches in the lower end and the bridge provided on one side with two ribs to enter the outermost notches, as shown 50 in Fig. 3, and on the other side with a single rib to bear on the lower end of the matrix, between the notches in order to hold it to a higher level.

The central notch shown in the matrices in Figs. 3 and 4 has no relationship to the present invention. It is employed for reasons unnecessary to describe herein and may be omitted without affecting the operation of the devices herein shown.

I believe myself to be the first to combine 65 with a distributor a means for delivering a series of matrices thereto—an adjustable means whereby the path of the matrices may be changed so that they will escape the distributor for delivery to a second distributor 70 elsewhere, as required—and it will be manifest to the skilled mechanic that the details of construction may be variously modified without passing beyond the limits of my invention.

Having thus described my invention, what I claim is—

1. In a linotype-machine the combination of a distributor and means adjustable at will 80 to direct advancing matrices to the distributor, or through a path clear of the distributor.

2. In a linotype-machine of the class shown, the upper distributor, X , in combination with means for delivering matrices thereto, said means including a member adjustable at will to permit the passage of the matrices clear of said distributor for delivery 85 to the lower distributor.

3. In combination the distributor-bar, the matrix-sustaining rails adapted to let the 90 matrices fall clear of the said bar, the notched matrices and the movable matrix-support to carry the matrices into engagement with the bar when required.

4. In a linotype-machine and in combination, the distributor-bar, the shouldered rails, x , the matrices notched at the lower end, and a matrix-support adjustable at will to enter 95 the notches or to act on the matrices outside of the notches as demanded.

5. In a linotype-machine, the combination of a distributor, means for delivering the matrices thereto, notched matrices, and the support, revoluble at will and constructed substantially as shown, to sustain the advancing 105 matrices at a high level or permit their descent to a lower level according to the position in which it is placed.

In testimony whereof I hereunto set my hand, this 7th day of October, 1905, in the presence of two attesting witnesses.

RICHARD M. BEDELL.
